PROCESS FOR THE REMOVAL OF CYANOGEN COMPOUNDS FROM GASES

Christian Johannes Hansen, Essen-Ruhr, Germany, assignor, by mesne assignments, to The Koppers Company of Delaware, Pittsburgh, Pa., a Corporation of Delaware

No Drawing. Application January 23, 1931,
Serial No. 510,846, and in Germany January 25,
1930

3 Claims. (Cl. 23—76)

This invention relates to a process for the removal of cyanogen compounds from gases.

The removal of cyanogen compounds from gases such as coal distillation gases by scrubbing with ammonium polysulphide liquors with the formation of ammonium thiocyanate has been proposed hitherto. In carrying out this process in the manner hitherto known considerable difficulty has been encountered owing to the fact that the absorption of the cyanogen compounds is much less complete as the temperature of the gases to be purified and of the wash liquor rises. As long as the temperature does not exceed 30° C. to 35° C. as, for example, is the case in a normal semi-direct process in coke oven practice or in the gas industry, the removal of cyanogen compounds does not present any particular difficulty. In such cases a mere washing of the ammonia-containing gas with an aqueous suspension of sulphur is sufficient.

If, however, the temperature of the gas and consequently also that of the wash liquor rises for whatever reason above the value given above, which may, of course, happen as a result of a breakdown in the cooling water installation, or when a part of the cooling installation is shut off for repair, then the washing out of the cyanogen compounds becomes very incomplete. For example, at a temperature of 50° C. to 60° C. it has not been possible hitherto to remove more than 20% to 30% of cyanogen compounds from gases with a normal content of one gramme of cyanogen compounds per cbm. calculated as HCN.

Apart from the loss in cyanogen nitrogen the dropping off in the efficiency of the cyanogen washing is particularly disturbing if the gas is to be given a further treatment for the removal of ammonia and sulphuretted hydrogen, for example, with alkaline iron thionate liquors which may also contain suspended iron hydroxide. In the latter case the cyanogen compounds and the iron salts form insoluble iron-cyanogen residues which may interfere seriously with the later operation of the washing process by stopping up the apparatus, and also with the working up of the spent wash liquors to pure ammonium sulphate and sulphur.

The surprising observation has now been made that cyanogen compounds can be removed completely from gases even when the temperature of

the said gases in the wash liquor rises above 30° C. for example to 60° C. to 70° C. so long as the wash liquor contains polysulphides in the form of higher polysulphides than the bisulphide.

Accordingly, the present invention comprises a process for the removal of cyanogen compounds from gases by bringing the latter into contact with an alkali polysulphide (for example ammonium polysulphide) liquor which process is characterized by employing a liquor containing polysulphides higher than the bisulphide and maintaining a sufficient excess of the said higher polysulphides in the liquor throughout the washing process to prevent the formation of monosulphides.

The presence of sufficient excess of higher polysulphides in the liquor is maintained according to the invention by adding to the liquor before or during the washing process at least one equivalent of sulphur and one equivalent of ammonia for each cyanogen group in the gas in the form of dicyanogen or hydrocyanic acid.

The characteristic effect obtained in the process according to the invention may possibly be explained on the assumption that sulphur can be added to bisulphide and higher polysulphides sufficiently rapidly at temperatures above 30° C. for example at 60° C. to 70° C. so that the higher polysulphides required for the combination with the cyanogen compounds, according to the following equations, can be regenerated directly by elementary sulphur:—

Against this the ammonium sulphide produced from ammonium disulphide, for example, according to the equation:—

can only be converted into disulphide by means of sulphur at temperatures considerably below 30° C. In other words a polysulphide wash liquor which contains mainly disulphide will be fully active at higher gas temperatures if ammonia and sulphur are added.

In order to test the efficiency of the liquor used in the process according to the invention or to make sure that it is composed in the manner hereinbefore specified, it should when acidified

not merely become slightly milky but should immediately give an opaque suspension of precipitated sulphur.

I claim:—

5 1. A process for the removal of cyanogen compounds from gases comprising bringing gases at a temperature above 30° C. and containing cyanogen compounds into contact with an ammonium polysulphide liquor containing polysulphides higher than bisulphides to remove the cyanogen compounds from said gases and maintaining a sufficient excess of the said higher polysulphides in the liquor throughout the washing process to prevent the formation of ammonium monosulphides.

10 2. A process for the removal of cyanogen compounds from gases comprising bringing gases at a temperature above 30° C. and containing cyanogen compounds into contact with an ammonium polysulphide liquor containing ammonium polysulphides higher than bisulphides to remove the cyanogen compounds from said gases and maintaining a sufficient excess of the said higher polysulphides in the liquor throughout the 15 washing process to prevent the formation of ammonium monosulphides.

15 ammonium monosulphides; excess of higher polysulphides being maintained in the liquor by adding thereto before the washing process a quantity of sulphur and ammonia not less in each case than one molecular equivalent for each cyanogen group contained in the gas in the form of dicyanogen or hydrocyanic acid. 80

20 3. A process for the removal of cyanogen compounds from gases comprising bringing gases at a temperature above 30° C. and containing cyanogen compounds into contact with an ammonium polysulphide liquor containing ammonium polysulphides higher than bisulphides to remove the cyanogen compounds from said gases and maintaining a sufficient excess of the said higher polysulphides in the liquor throughout the washing process to prevent the formation of ammonium monosulphides; excess of higher polysulphides being maintained in the liquor by adding thereto during the washing process a quantity of sulphur and ammonia not less in each case than one molecular equivalent for each cyanogen group contained in the gas in the form of dicyanogen or hydrocyanic acid. 85 90
